UNITED STATES PATENT OFFICE

158,765

UMBRELLA

Charles Katz, Baltimore, Md.

Application March 3, 1949, Serial No. 1,203

Term of patent 3½ years

(Cl. D88—3)

To all whom it may concern:

Be it known that I, Charles Katz, a citizen of the United States of America, residing at Baltimore, independent city of Baltimore, and State of Maryland, have invented a new, original, and ornamental Design for an Umbrella, of which the following is a specification, reference being had to the accompanying drawing, forming a part thereof.

In the drawing:

I claim:

The ornamental design for an umbrella, as shown.

CHARLES KATZ.
